UNITED STATES PATENT OFFICE.

EUGENE E. MESSMORE AND WILLIAM SEVERN, OF EPWORTH, IOWA.

AUTOMATIC OILER.

No. 911,513.

Specification of Letters Patent.

Patented Feb. 2, 1909.

Application filed February 18, 1903. Serial No. 416,574.

To all whom it may concern:

Be it known that we, EUGENE E. MESSMORE and WILLIAM SEVERN, citizens of the United States, residing at Epworth, in the county of Dubuque and State of Iowa, have invented new and useful Improvements in Automatic Oilers, of which the following is a specification.

This invention relates to an automatic oiling device for wind mills, machinery or the like, and the object of the invention is to provide a device of this character, having a trip wheel adapted to be struck by the working part of the machine and to revolve a shaft having oil receiving pockets positioned directly below an oil tank and to deposit the oil upon an element where it is directed to a series of conveying tubes leading directly to the parts of the machine to be oiled.

Another object of the invention is to provide a device of this character, whereby a single drop of oil is deposited upon an element and conveyed to a suitable tube leading to the parts of the machine to be lubricated, a plurality of tubes being employed, each leading to separate parts of the machine, and each adapted to deposit a single drop of oil in rotation as the oil receiving element is revolved.

With these and other objects in view the invention resides in the novel construction of elements and their arrangement in operative combination, hereinafter fully described and claimed.

In the drawings, Figure 1 is a central longitudinal section of a device constructed in accordance with our invention. Fig. 2 is a vertical transverse sectional view upon the line 2—2 of Fig. 1. Fig. 3 is a horizontal sectional view upon the line 3—3 of Fig. 1.

In the drawings the numeral 1 designates a suitable casing, having its bottom wall 2, provided with a series of radially disposed openings 3, adapted for the reception of a plurality of conveying tubes 4. The bottom 2 is also provided with an opening 5 centrally located in regard to the annularly disposed openings 3, and this opening 5 is adapted for the reception of a pintle 6, supporting an oil receiving and depositing element 7. This element 7 has its upper face provided with an oil receiving chamber 8, communicating with an oil channel 9, which in turn communicates with an opening 10, arranged upon the element 7 directly above

the openings 3. The element 7 has its periphery rounded and provided with teeth 11, adapted to mesh with a worm 12, provided upon a shaft 13, suitably mounted in openings or bearings provided upon two of the sides of the casing 1. The shaft 13 is adapted to extend a suitable distance beyond one of the sides of the casing, and this extended portion is provided with a trip wheel 14. The trip wheel 14, may be constructed in the form of a star, as illustrated in the drawings, or may be of any desired formation, so as to provide arms adapted to be contacted with a working element of the machine to be oiled.

Arranged upon the sides of the casing 1, transverse to the shaft 13 is a tapering axle 15, provided with a toothed wheel 16, adapted to mesh with and be operated by the worm 12. The tapering axle 15 is provided with a suitable oil receiving pocket 17, and this pocket 17 is adapted to align with a vertical opening or channel 18, provided within a nipple 19. The nipple 19 has an upwardly extending portion 20, which is adapted for attachment with a suitable oil tank or reservoir 21. The offset portions of the nipple extension 20 are provided with a tapering bore adapted for the reception of the axle 15. The channel 18 is extended vertically the entire length of the nipple, so as to provide an outlet opening 22, positioned directly above the oil receiving chamber 8 of the member 7. The oil tank 21 is provided with a suitable cap, whereby access to the interior of the tank is obtainable when oil is to be deposited within the tank.

The operation of the device is as follows: When the working part of the wind mill or machine to which our automatic oiler is attached, contacts with the trip wheel 14, the shaft 13 and worm 12 are rotated and in turn rotate the cog wheel 16 and the shaft 15, causing the oil deposited from the tank 21 within the pocket 17 of the axle 15 to be deposited through the opening 22 of the nipple 19 within the chamber 8 of the element 7, and to flow through the channel 9 through the opening 10 and upon the flared mouth of one of the openings 3 and thence through the conveying tubes 4 to the portion of the machine to be oiled, it being seen that the revolution of the worm 12 likewise rotates the member 7 and brings the opening 10 directly over the openings 3 in rotation, 110

thus furnishing a quantity of oil successively to the different parts of the machine, through the conveying tubes 4, as the element 7 is revolved.

5 Having thus fully described the invention what is claimed as new is:

1. An oiling device comprising a casing having an oil tank and a series of openings provided with conveying tubes, a shaft having an oil pocket, a toothed wheel upon the shaft, a transverse axle having a worm engaging the toothed wheel, a trip wheel upon the axle, an oil receiving and conveying element having peripheral teeth engaging the worm mounted within the casing, the element being provided with an opening adapted for alignment with the openings provided by the casing.
- 10 2. An oiling device comprising a casing having a plurality of openings provided with conveying tubes, a rotary element hav-

ing an opening alining with the openings of the casing, teeth upon the periphery of the element adapted for engagement with a worm, a shaft for said worm mounted upon 25 the casing, a trip wheel upon the shaft, a transverse tapering axle within the casing, a toothed wheel upon the axle adapted for engagement with the worm, the axle being provided with a pocket adapted to aline with 30 an opening provided by a nipple secured to the casing, and an oil tank communicating with the opening provided by the nipple, the pocket of the axle adapted to aline with the center of the rotary element.

35 In testimony whereof we affix our signatures in presence of two witnesses.

EUGENE E. MESSMORE.
WILLIAM SEVERN.
